CLAIM

The ornamental design for a sidewall for a bottle, as shown and described.

DESCRIPTION

FIG. 1 is a perspective view of a sidewall for a bottle showing our new design, the appearance of the sidewall for a bottle repeats four times around the central vertical axis; FIG. 2 is a right side view thereof; FIG. 3 is a left side view thereof; FIG. 4 is a top plan view thereof; and, FIG. 5 is a bottom plan view thereof.

The broken lines shown in FIGS. 1 through 5 are for illustrative purposes only and do not form part of the claimed design.
